BESSE OLDEN MASON, OF EAST ORANGE, NEW JERSEY, ASSIGNOR TO JAMES McCREERY & COMPANY, OF NEW YORK, N. Y., A CORPORATION OF NEW YORK.

HAT.

Application filed April 1, 1925. Serial No. 19,907.

My invention relates to improvement in hats and more particularly hats for ladies' wear. Moreover the invention is especially applicable to the style of hat now much in vogue which fits down well over the top of the head. Much difficulty is experienced in getting hats of this style to fit and particularly in view of the different ways of wearing the hair. My invention is intended to obviate this difficulty and produce a simple hat which will cost no more than the ordinary and by which the size can be quickly adjusted to fit any head. The difficulty in accomplishing this result arises from the fact that a hat must be ornamental in order to be popular and any adjustment must be such as will not detract from the beauty of the hat and in producing my invention I have had this in mind and one object is to produce an attachment or means of adjustment which will actually beautify the hat and make it more attractive than similar hats that do not have the adjustment.

Reference is to be had to the accompanying drawings forming part of this specification, in which similar reference characters indicate corresponding parts in all the views.

Figure 1 is a side elevation of a hat showing my improvements.

Figure 2 is a similar view but from the opposite side.

Figure 3 is a perspective view, the hat brim turned partly down and partly up to show the adjustable feature.

Figure 4 is a perspective view of a slightly modified type of hat.

Figure 5 is a detailed section, illustrating the means of adjustment.

By way of example the drawings represent a hat of general conventional type, that is the soft or felt hat which fits the head rather closely and this is provided with a brim which may be turned down or up and which has overlapping parts 11 and 12 split or separated diagonally as shown at 13 and these overlapping parts are preferably placed at the front of the hat. The edges of these parts are gradually narrowed and merge at the back of the hat to a hardly perceptible brim 13a. Obviously, any particular form and style of the brim can be adopted without affecting the invention. By having the brim of the general shape indicated and separated along the line 13 the handsome outlines of the hat can be pre-

served and when the brim is turned up and the parts overlapped as in Figures 1 and 2, the said parts serve to ornament the hat and relieve its rather severe outlines.

These overlapping parts 11 and 12 can obviously be connected by any adjustable means, but from the character of the invention these means should be ornamental, therefore I prefer to use ribbons as illustrated, and to this end the ribbons 14 can be ornamented where they join the brim flaps 11 and 12 as shown at 15 and where the ribbons connect it may be by means of a buckle 16 of some ornamental character which will be at the back of the hat. As shown, this buckle 16 has a keeper 17 on the back which can be sewn or otherwise fastened to the hat crown, and the buckle has a flexible finger 18 which may be punched through the overlapping parts of the ribbon 14 to prevent them from separating and to fix the head size. It will be, of course, evident that the ribbon ends can be connected by any suitable buckle or other fastening device or may be tied with a bow or knot, without affecting the invention. It will also be understood that the ribbons or equivalent parts may be fastened together at other points than the back of the hat. Instead of having the flaps 11 and 12 overlap as shown, one may be slotted transversely as shown at 12a in dotted lines so that the other flap may extend through it. Likewise it should be apparent that the ribbons or fastening may be guided in any desired way. For instance, in Figure 4 I have shown a slightly different style hat in which the top is what is sometimes termed the mellon top, and the ribbons 14 are extended through slits 19 in the side of the crown which thus act as keepers. The fastening members or ribbons 14 extend in opposite directions around the crown of the hat, and each exerts on its respective brim portion 11 and 12 a lateral, circumferential pull, which draws said brim portion into close and snug engagement with the crown of the hat, producing a neat and trim effect.

From the foregoing description it will be seen that the essential thing is to have a take-up or overlapping part in some portion of the hat opposite that which comes in contact with the head and with means of adjusting this part to make the hat fit the head nicely. Bearing this in mind it will be understood that the hat can be made in many styles and

of different materials without departing from the disclosed invention.

I claim:

- 5 1. A hat comprising a complete well defined crown, a marginal brim at the lower edge of the crown, said brim being of varying height, and having a diagonal split therein forming overlapping reduced end portions, and fastening bands secured to the end portions of the brim and arranged to fasten around the lower part of the crown thereby binding the brim against the crown.
- 10 2. A hat comprising a well-defined complete crown merging into a marginal brim, the brim being split so that the ends thereof

over lap, and fastening members attached to and forming extensions of the overlapping ends of the brim, said fastening members extending in opposite directions from the split and each exerting a lateral 20 circumferential pull on the brim portion to which it is attached, the lateral circumferential pull exerted by said fastening members on the brim serving to hold said brim snugly against the crown.

25 In testimony whereof, I have signed my name to this specification this 27th day of March, 1925.
